UNITED STATES PATENT OFFICE

1,982,655

WINDOW

Samuel W. Funk, Charter Oak, Calif.

Application March 30, 1933, Serial No. 663,535

8 Claims. (Cl. 20—53)

My invention relates to a window of a type illustrated in my United States Patent No. 821,353 of May 22, 1906, for Tight and noiseless casements for swinging closures.

5 An object and feature of my invention is a pivoted sash in which resilient weather strips form a seal or closure on the window frame at all sides of the window, when such window is closed. That is presuming that the sash is pivoted at the sill and soffit of a window frame, the sash when closed on account of having the weather strip mounted on the sash will form a tight closure against not only the soffit and the sill but the two side jambs of the window frame.

10 Another object and feature of my invention is in a pivoted type of sash to provide a resilient weather strip on the sides having the pivots so that these weather strips will contact with flat surfaces in which the pivots are mounted to turn, thus if the sash is pivoted in the soffit and sill of a window, the resilient weather strip engaging the soffit and the sill holds the window at any desired degree of opening without any other holding or adjusting features.

15 Another further object and feature of my invention is the employment of a means for adjusting the projection of the resilient weather strip from the frame of the sash. This is obtained by the construction of a sash formed of two separable parts which engage the resilient strip and also by expansion springs which force the weather strip, which is preferably rubber, outwardly.

Another feature of my invention as relates to its employment in vehicles is the mounting of the sash in such a manner that when the vehicle is proceeding in a forward direction so that the general flow of air is along the vehicle, the sash may be set to create a partial vacuum on the outside of the vehicle so that air is sucked from the inside to the outside.

In this connection another detail feature is the construction of the side or jamb edges of the window whereby a small arcuate swing of the sash gives a relatively large opening. This is caused by forming the jamb sections of the window convex in cross section.

My invention is illustrated in connection with the accompanying drawing, in which:

Fig. 1 is a horizontal section through a door or a window suitable for a motor vehicle.

Fig. 2 is an elevation of a sash suitable for a building.

Fig. 3 is a horizontal section through a window suitable for a train or electric car which goes in opposite directions.

Fig. 4 is a section on the line 4—4 of Figure 3 in the direction of the arrows through one of the pintles.

Fig. 5 is an edge view of the expansion spring used to press the weather strip outwardly, taken 60 on the section line 5—5 of Figure 3 in the direction of the arrows.

Fig. 6 is a transverse section through a modified sash frame showing the manner of holding the rubber weather strip.

Referring first to the construction of Figures 3 and 4, I illustrate a window frame 11 which may be considered as having a sill 12. This has a flat upper surface 13. The soffit is the same and also has a flat lower surface. The two side jambs 14 70 of the window have center sections 15 formed on a convex curve. The outer portions 16 may have a reverse curve or any type of suitable molded shape extending to the outside and inside edge of the window jamb. The sill and soffit are provided with pintle sockets 17 in which there is preferably inserted a bushing 18 which may be of hard rubber or some other material which will not rattle.

The same type of sash is shown substantially 80 in all the figures, the sash of Figure 2 being substantially the same as that of Figures 3 and 4. The window sash 19 employs a metal frame 20 which holds the glass 21. The metal frame is shown as having similar inside and outside frame 85 bars 22. These frame bars each have an inwardly pressed section 23 through which are screws 24 spaced longitudinally of the frame. The screws clamp the glass between the jaw sections 25 of the frame and also clamp resilient weather 90 strips 26 between the outside jaws 27. The weather strip is illustrated as formed of two flat strips of rubber held tightly together by the two jaws.

The pintles 28 each fit in a bushing 18. A 95 pintle plate 29 forms an extension of the pintle and is secured to the side bars of the frame by screws 30 as illustrated in Figure 2. Each pintle plate is illustrated as having a shoulder 31 which is held spaced from the sill surface and the soffit 100 surface by the projecting rubber weather strip on the pintle sides of the frame.

In order that the weather strip may be pressed outwardly to facilitate adjustment, a compression spring assembly 32 is fitted between the jaw 105 portions of the frame bars carrying the weather strip. This spring assembly has two strips 33 and 34 which are held spaced apart by a wave formed spring 35. This latter spring is resilient and tends to press the strips 33 and 34 apart. 110

Thus when the spring assembly is fitted between the frame bars one strip 34 bears against the inside edge of a weather strip section and when the screws 24 are loosened tends to force the weather strip outwardly. This permits adjusting to form a tight fit between the weather strip at the sides having the pivots and also the sides of the window having the convex jambs.

At the corners of the frame there are corner angle pieces 36 which join adjacent corners together, or these corners may be formed in any suitable manner. A handle 37 is attached to the frame by being secured to one of the frame bar assemblies, thus facilitating the opening and closing of a window.

The window is operated and functions as follows. On account of the pintles being through flat surfaces, for instance at the top and bottom of a sash, the weather strips on the sides of the sash having the pintles will bear against the flat surfaces of the frame. Thus if the sill and the soffit of the window is flat and the pivots are in the soffit and the sill, the rubber weather strip engaging these flat surfaces will hold the window in any desired degree of opening. The window may be opened by either pulling or thrusting on either side edge towards a jamb of the window. This will swing the sash into an angular position such as shown in Figure 1. Presuming, therefore, that there is a movement of air on the outside in the direction of the arrow 38, which would occur if the sash were on a vehicle moving in a direction to cause such air pull, then a partial vacuum will be created outside of the sash and cause an outward flow of air in the direction of the arrows 39 and 40. One of the objects of having the jambs formed convex, as shown at 15, is that a slight arcuate movement of the sash will give a larger opening between the weather strip adjacent the jamb than if the jamb were made flat. Also on account of the pivot being offset at one side from the rubber weather strip at the pivoted portions there is a slight movement of translation as well as an arcuate movement of the weather strip on the sides of the sash in reference to the jamb. This movement is readily accommodated by the convex shape of the jambs and also by the resiliency of the weather strip.

In the construction shown in Figure 1 the window or door frame 42 is illustrated as having a sill 43, the soffit would be the same, and a jamb 44 on one side and another jamb 45 on the opposite side. The sill is illustrated as having a slot 46 in which there is a vertical sliding glass window 47. This window is indicated as having a metal frame 48. This frame on one edge forms a jamb for engaging one side of the pivoted sash. The other side is engaged by the jamb 44.

In the construction of Figure 6 the frame bar assembly 49 is illustrated as made of a single strip of metal formed with two return bends 50 with a jaw 51 formed between the reverse bend sections. The free edges 52 engage the resilient weather strip 53 and the two side portions 54 are attached by screws 55. The expansion springs 56 are secured forming a backing for the resilient weather strip and also bearing against the screws. The screws are attached to the frame bars so that the heads of the screws are on the inside of the window. Therefore, the frame bars cannot be disassembled from the outside with the use of a screwdriver.

Various changes may be made in the details

of construction without departing from the spirit or scope of my invention as defined by the appended claims.

I claim:

1. A window sash having a frame with a glass therein, pivots diametrically opposite connected to two opposite sides of the frame, the frame having weather strips adjustably mounted therein, and a spring positioned back of each strip tensioned to force the strip outwardly, the spring having a pair of parallel strips with a spring in between formed with wave like corrugations.

2. A window having a sill and a soffit with parallel flat surfaces and opposite jambs with convex surfaces facing each other, a sash having a frame with glass therein, rubber weather strips on all sides of the frame in the plane of the glass, a pivot secured to the top and bottom of the frame, one pivot being journaled in the soffit and the other in the sill, the pivots being offset to one side of the plane of the weather strip, the strip on the sill supporting the frame above the sill and the weather strips on the sides contacting with the convex surfaces of the jambs when the window is closed, the frame and the sash having parallel jaws with the weather strip inserted between said jaws, and screws through the portion of the frame adjacent the jaws to clamp the jaws on the weather strip.

3. A window as claimed in claim 2, the frame having opposite side members with inwardly pressed sections, the screws extending through the inwardly pressed sections, the weather strips being clamped between the jaws by the screws, and a spring structure between the jaws bearing against the back of the weather strip and also against the inwardly pressed sections of the frame.

4. A window sash having a glass, a frame formed of opposite strips having inner jaws engaging the marginal portion of the glass, the said strips having outer jaws with rubber weather strips therein, screws connecting the said strips to clamp the jaws engaging the glass and the jaws engaging the weather strip, and pintles secured to the frame.

5. A window sash as claimed in claim 4, a spring comprising two straight strips and a waved strip therebetween, the said spring being inserted into the outer jaws behind the weather strip to force said strip upwardly.

6. A window sash having a glass, a frame surrounding the glass having two metal strips with inner jaws engaging opposite sides of the glass adjacent its marginal edge and having outer jaws engaging a rubber weather strip, each strip having an inwardly pressed section, screws extending through inwardly pressed sections and holding the strips together, and pintles secured to opposite sides of the frame.

7. A window sash having a frame formed of a strip of sheet metal having an inner jaw formed by two reverse bends, the inner jaw engaging the marginal portions of the glass of the sash, a weather strip engaged by the outer edges of the strip which form an outer jaw, screws attaching both sides of the strip together and clamping the weather strip in position.

8. A window sash as claimed in claim 6, a spring fitted in the outer jaw between the weather strip and the screws operative to force the weather strip outwardly.

S. W. FUNK.
